UNITED STATES PATENT OFFICE.

JOSEPH R. GUMP, OF MILAN, MICHIGAN.

CHECKREIN-HOOK.

SPECIFICATION forming part of Letters Patent No. 595,566, dated December 14, 1897.

Application filed December 14, 1896. Serial No. 615,668. (No model.)

To all whom it may concern:

Be it known that I, JOSEPH R. GUMP, a citizen of the United States, residing at Milan, in the county of Washtenaw and State of Michigan, have invented certain new and useful Improvements in Checkrein-Hooks, of which the following is a specification, reference being had therein to the accompanying drawings.

The invention consists in the construction of a checkrein-hook designed to facilitate the disengagement of the checkrein after being once engaged, and is an improvement upon the device shown and described in United States Letters Patent No. 565,268, granted to me August 4, 1896.

The invention consists in detail in the construction, arrangement, and combination of the various parts, as more fully hereinafter described and claimed.

20 In the drawings, Figure 1 is a sectional elevation of my improved hook, showing it closed. Figs. 2 and 3 are similar views showing it fully and partially open.

25 A is the base, having suitable securing means, such as the stub-bolt B, and provided at the top with a **U**-shaped hook C. The forward arm *a* of this hook is made with a groove *b*, which is formed between the side flanges *c*, the side flanges merging into the base. The 30 rear arm *d* is bifurcated, or is formed simply by the extension of the flanges alone. In the bifurcation of the rear arm is a substantially **C**-shaped locking-frame D, pivoted on the transverse pin E, and having projecting from 35 near its pivotal point the actuating arm or lever F. This locking-frame has a checking-arm G, which lies between the bifurcations of the arm *d*, and its outer end fits in the groove in the forward arm. The upper arm H of this 40 frame is adapted to bridge the space between the tops of the two arms *d a*.

45 In the upper end of the arm *a* and lying within the groove in that arm is a spring-catch I, provided at its upper end with a bend or shoulder J. The arm H is provided with a

locking-tongue J', which is provided with a corresponding recess in which the shoulder of the spring-catch is adapted to engage to hold the parts in the closed position shown in Fig. 1.

50

The arm G is of such a length and so arranged that in its opening movement it will bear against the spring-catch, cleaning out any dirt or dust that may have accumulated therein in use, and as its end reaches the 55 shoulder on the spring it is forced above the same, as shown in Fig. 2, in which position the spring maintains the hook in its open position, so that the operator can more readily remove the checkrein without the interference of the hook.

60

By using the spring-catch I and arranging it so that it conforms to the inner face of the hook within the groove I obtain a long easy working spring which permits me to engage and disengage the locking-frame with little effort and without danger of its breaking with any ordinary use, the spring being protected by being locked in the groove and kept clean and free from dust by the action of the arm G. 70

What I claim as my invention is—

In a checkrein-hook, the combination with a base and securing means, of a substantially **U**-shaped frame thereon, a shouldered locking-spring at or near one end of the frame, and a substantially **C**-shaped hook pivotally secured to the opposite branch of the frame, one end having a locking-shoulder thereon arranged to engage the shoulder of the spring and the opposite end being formed of a length sufficient to carry its end outward to a point to engage the said spring-shoulder and rest thereagainst when the hook is in its open position, substantially as described.

75

In testimony whereof I affix my signature 80 in presence of two witnesses.

JOSEPH R. GUMP.
